Inventor

By his Attorney, Irvin H. Kaufman,

J. Wooster.

UNITED STATES PATENT OFFICE.

IRVIN H. KAUFMAN, OF NEW YORK, N. Y., ASSIGNOR TO THE BLACKBURN-SMITH CORPORATION, A CORPORATION OF NEW YORK.

ELECTRIC SWITCH.

1,331,929.

Specification of Letters Patent. Patented Feb. 24, 1920.

Application filed September 21, 1918. Serial No. 255,075.

To all whom it may concern:

Be it known that I, IRVIN H. KAUFMAN, a citizen of the United States, and resident of the city of New York, in the county of New York and State of New York, have invented certain new and useful Improvements in Electric Switches, of which the following is a specification.

This invention relates to electric switches, and has for its object to provide a simple and positively operating form of quick make and break switch especially adapted to be controlled by a float, rod or the like. The mechanism is preferably inclosed in a case so as to be protected from noxious vapors or gases, and is made compact so as to go in a small space.

The accompanying drawings show a preferred form of the invention wherein—

Figure 1 is a front elevation, with the cover removed;

Fig. 2 is an end elevation;

Fig. 3 is a rear view.

The mechanism comprises a pivotally movable arm 1, carrying a pivoted contact block 2, coöperating with fixed carbon contacts 3, 3, mounted in separate terminal blocks 4, 4, on insulating base 5. The pivoted contact block is composed of insulating material and carries a conducting bridge 6 which closes the circuit across contacts 3, 3, when the switch is closed. The contacts 3, are replaceable and adjustable in the blocks 4, being fastened by screws 7, 8, 9, are the line wires which lead in through the nipple 10 on the base 11 of the casing. The usual armored conduit is attached to the nipple 10. 12 is the removable front cover. 13 is a small spring bearing on the contact block 2 for holding its edge parallel to the contacts 3, but yielding when necessary to enable good contact to be made with both contacts 3.

The actuating means consists of a bell crank pivoted to the case 11 and having its external arm 14 resting between collars 15 on a float or otherwise actuated rod 16, and its inner end 17 carrying a link 18 with roller 19 held on the spear head or cam end 20 of arm 1 by spring 21. 22 is an interior stop for the arm in open position, and 23 is an outside stop for the lever arm 14 in slot 24 of counterweights 25. 22 is a lug carried by the base 11 for limiting the switch move-

ment, and 26 is a lug for mounting the switch where desired.

In operation, movement of the arm 14 causes the roller 19 to move on the curved cam surface 20 toward the point while stretching spring 21 to store up sufficient power to thickly throw the main switch arm 1 as soon as the roller passes sufficiently far past the center of the cam 20. This forms a simple and sure means for quickly operating the switch with a minimum of arcing, and since spring 21 is always stronger than spring 13, the circuit is always tightly closed across contacts 3 by positive pressure of spring 21. Moreover, a good surface contact is provided, which is increased by slightly channeling the contacts 3 to fit the rounded contour of connecting bridge 6. The switch complies with all underwriters' requirements and does not have any live parts beyond the terminals and contact blocks 3, 4, and the bridge 6. Owing to its structure it will resist noxious vapors and gases, and is still further protected by the complete inclosing casing.

Various modifications and changes may be made without departing from the scope of the appended claims.

I claim:

1. A switch comprising a stationary contact, a movable arm carrying a contact, a double actuating cam on said arm, a lever mechanism having a link engaging said cam, and a spring holding the link engaged with the cam and throwing the cam and arm as the lever is operated to move the link on said cam.

2. A switch comprising a stationary contact, a movable arm carrying a contact, a double actuating cam carried by said arm, and a bodily movable link and a spring for actuating said cam through power stored in the spring by movement of the link.

3. In a switch, separated line terminals, a switch arm insulated therefrom and carrying a pivoted bridging conductor, means holding the conductor in position to align with both terminals, a cam carried by the said arm, a floating lever in rolling pressure engagement with said arm and means whereby the pressure of the lever on the cam is increased upon a predetermined movement of the lever to actuate the cam.

4. In a switch, a casing, a line terminal

- block, a switch arm insulated therefrom and carrying a pivoted contact block, means holding the contact block in predetermined position, a double cam carried by the said arm, a lever journaled on the casing having an external and an internal arm, a lever connected to said arm in pressure rolling engagement with the said cam, the said lever exerting pressure through said cam on said 10 arm first in one direction and then in the reverse direction to actuate said arm during the operation of the said lever in one direction and stopping means for the arm.
5. In a switch, a casing, a rock shaft hav-

ing an arm, a link connected to said arm, 15 a roller carried by said link, a spring connected to the mid portion of said link and to the casing, a pivoted switch arm having a double cam for said roller and movable back and forth as said shaft is rocked.

20

Signed at New York in the county of New York and State of New York this 16th day of September A. D. 1918.

IRVIN H. KAUFMAN.
